UNITED STATES PATENT OFFICE.

MELVILLE C. BARNARD, OF DOUGLAS, ARIZONA.

DESIGN FOR A BADGE OR SIMILAR ORNAMENT.

52,261.

Specification for Design.

Patented Aug. 20, 1918.

Application filed April 3, 1918. Serial No. 226,549. Term of patent 3½ years.

To all whom it may concern:

Be it known that I, MELVILLE C. BARNARD, a citizen of the United States, residing at Douglas, in the county of Cochise and State of Arizona, have invented a new, original, and ornamental Design for a Badge or Similar Ornament, of which the following is a specification, reference being had to the accompanying drawing, forming part thereof, and in which—

The figure is an elevation of a badge, showing my new design.

I claim:

The ornamental design for a badge or similar ornament, as shown.

MELVILLE C. BARNARD.

Copies of this patent may be obtained for five cents each, by addressing the "Commissioner of Patents, Washington, D. C."
